United States Patent Office

Des. 184,541
Patented Mar. 3, 1959

184,541

PHOTOGRAPHIC CAMERA

Robert L. Smith, Deerfield, Ill., assignor to Bell & Howell
Company, Chicago, Ill., a corporation of Illinois

Application September 19, 1958, Serial No. 52,701

Term of patent 14 years

(Cl. D61—1)

FIG. 1.

FIG. 2.

I claim:

The ornamental design for a photographic camera, as shown.
